TIMED TRIPPING DEVICE

Jacob W. Ogden, Springdale, Conn., assignor to
 Pitney-Bowes Postage Meter Co., Stamford,
 Conn., a corporation of Delaware

Application June 9, 1936, Serial No. 84,286

21 Claims. (Cl. 101—235)

This invention relates to a machine for printing stamp impressions on letters and the like, and more particularly to the means for tripping or actuating the printing device, which means is adapted to be controlled to delay the actual printing operation for a predetermined period after the normal trip, which is actuated by means of an approaching letter, is effected.

The device of this invention is adapted for use with a class of machines commonly known as metered mailing machines and is particularly arranged for use with the type of machine which is illustrated and described in U. S. Letters Patent Reissue No. 15,734.

In a machine of this type a value stamp is printed upon letters which are conveyed past a printing position and the money value thereof is registered in a metering device. A trip member which is positioned in the path of the approaching letters is adapted, when engaged by a letter, to trip a clutch, whereby the printing device will be operated to print the said stamp impression, which process is repeated for each letter moved into engagement with the trip.

In the device of this invention, means is provided for controlling the position of one or more imprints upon a letter, which device generally comprises a timing element arranged in a cooperative relation between the letter actuated trip member and the printing member actuating means, and which when actuated by the letter trip is adapted to delay the operation of the printing member for a predetermined period or until the letter has advanced to a desired position for the reception of the imprint.

It is the principal object of this invention therefore, to provide a timing device to set the printing member in operation, which is adapted to be actuated by a letter tripping device.

It is a further object to provide means whereby an imprint may be made on a letter or other article in any one of a plurality of predetermined positions.

With the foregoing and other objects in view which will appear as the description proceeds, the invention resides in the combination and arrangement of parts and in the details of construction hereinafter described and claimed, it being understood that various changes in the precise embodiment of the invention herein disclosed may be made within the scope of what is claimed without departing from the spirit of the invention.

A preferred embodiment of the invention is

illustrated in the accompanying drawings, wherein:

Fig. 1 is a plan view showing a portion of a metered mailing machine immediately surrounding the printing device, including the envelope 5 tripping means also the trip setting means;

Fig. 2 is a front elevational view looking in the direction of arrow 2 on Fig. 1;

Fig. 3 is a plan sectional view taken along the lines 3—3 of Fig. 2 particularly for the purpose 10 of showing the tripping device and parts associated with the main clutch;

Fig. 4 is a plan sectional view of the printing die including the postmark die;

Fig. 5 is a front elevational view on an enlarged 15 scale of a portion of the mechanism shown in Fig. 2 of the delayed tripping unit;

Fig. 6 is a plan sectional view taken substantially along the line 6—6 of Fig. 5 showing the delayed tripping unit with the trip roller in its 20 #1 tripping position and the trip actuating member about to be tripped by an approaching letter;

Fig. 7 is a plan sectional view taken along the line 7—7 of Fig. 5 with the parts in their normal 25 untripped position and particularly showing a latch structure which is associated with the secondary clutch mechanism;

Fig. 8 is a vertical sectional view taken along the line 8—8 of Fig. 6;

Fig. 9 is a horizontal sectional view taken along the same plane as Fig. 6 with parts broken away and showing the trip actuating member in a tripped position as caused by the passing letter and further showing the latch mechanism associated with the secondary clutch in a released position;

Fig. 10 is a horizontal or plan sectional view taken on substantially the same plane as Fig. 6 with parts broken away and showing the clutch 40 tripping roller, which is adapted to trip the main clutch, as having moved past the clutch tripping cam member;

Fig. 11 is a fragmentary detail view showing a portion of a letter with a single stamp impression 45 and postmark impression thereon;

Fig. 12 is a similar view to that of Fig. 11 showing a plurality of stamped impressions also the postmark stamp thereon;

Fig. 13 is a fragmentary detail view showing 50 a portion of a tax receipt card or the like with tax impressions thereon;

Fig. 14 is a fragmentary detail view showing a modified arrangement of adjustment for the secondary clutch; and

Fig. 15 is a further fragmentary detail view showing another modified arrangement of adjustment for the secondary clutch.

Referring to Figs. 1, 2 and 3, the letter feed 5 tripping and the general structure of the mechanism for operating the main clutch will be described.

Referring to Fig. 1 letters L are conveyed from a source of supply by means of feed rollers 15, 10 between suitable guides 14, past a trip finger 16, then between a printing die 17 and an impression roller 18 to receive a stamp impression. The letter is then ejected by means of ejector rollers 19-19 to a suitable receiver or stacker, not 15 shown.

The trip finger 16, which is tripped when engaged by a letter, is indirectly connected with a main clutch member 21, Figs. 2 and 3, which clutch member is directly connected with the 20 printing die member 17 and is adapted to be driven by means of a continuously driven gear 22 when tripped. Associated with said main clutch member 21 is a stop arm 23 Fig. 3 which forms one arm of a three armed rocker member 24. Another arm 25 extends outward from said 25 rocker member 24 and a third arm 26 extends substantially downward therefrom.

The clutch 21 is normally urged to rotate in the direction of the arrow shown in Fig. 3 and, 30 upon release of the stop arm 23 from its engagement with a shoulder portion 27a of a flange 27 on said clutch member 21, said clutch will rotate through one revolution to thereby rotate the printing die 17 through one revolution. The 35 rocker member 24 is normally urged to rotate in a counter-clockwise direction through the spring actuated structure indicated at 28, which is adapted to apply a pressure against the outwardly projecting arm 25 in the direction indicated by the arrow.

Associated with the rocker member 24 is an abutment member 29 which is pivotally mounted upon a shaft 31 and has a roller 32 rotatably mounted upon one end of an arm 33, which roller 45 is adapted to be normally maintained in engagement with a roller 34 mounted on the arm 25 of said rocker member 24. The abutment roller 32 is normally maintained in an abutment position by means of a spring 35, which spring normally 50 maintains a downwardly extending arm 36 of the abutment member 29 against a fixed stop 37.

Upon rocking said abutment arm 29 from the full line position of Fig. 3 to the dotted line position, the rocker arm 24 will be urged from its 55 full line position to the dotted line position by means of the spring actuated structure 28, whereupon the clutch 21 will be released and will rotate through one cycle or revolution. The limit of said clutch movement is controlled by means of a roller 38 mounted on the arm 26, which is adapted to be engaged by the flange 27 to rock the stop arm 23 into the path of the shoulder 27a of said flange.

Also connected with the arm 36 is a pull rod 65 39 which has a shoulder portion 41 on its opposite end yieldably maintained in contact with the end of a trip arm 42 by means of a spring 43. The trip arm 42 is mounted upon a shaft 44, upon which shaft the trip finger 16 is also 70 mounted.

The structure as thus far described is the same as that described in said Reissue Patent No. 15,734. As utilized in the structure of said patent, the rocking of the trip finger 16, when engaged by a letter, was adapted to rock the shaft

44 which in turn would rock the trip arm 42 to directly actuate the clutch trip or rocking member 24.

In the device of this invention however, an intermediate or secondary clutch device is provided for the purpose of delaying the tripping action of the trip arm 42.

To obtain the latter result, the trip finger 16 is freely mounted to rotate upon the shaft 44, through the engagement of a boss 46a therewith, and has a keyed connection at 48 with a sleeve 45 also on said shaft 44, as best shown in Fig. 5. Said sleeve is also keyed at 50 to a boss portion 28a of a lever 46 at the lower end thereof, which lever has mounted upon its lower surface, a latch 15 tripping arm 47. See Figs. 5, 7 and 9. Therefore, upon operation of the trip finger 16, by means of the engagement of a letter therewith, the movement of said trip finger 16 will directly effect the operation of the latch tripping arm 47. 20 The secondary clutch is controlled by said latch arm 47 and includes a ratchet gear 48, having trunnions 51-51 rotatably supported in bearings 51-51, which ratchet is continuously driven by means of a gear 49 to which it is adapted to be 25 attached, as by means of a pin 30. See Figs. 8 and 9.

As best shown in Fig. 7, suitable driving pawls 52-52 are pivotally mounted upon pins 53-53, which pins have their opposite ends secured in 30 upper and lower plates 54-54, positioned above and at the lower end of the ratchet gear 48.

The pawls 52-52 are normally held out of engagement with the ratchet gear 48, by means of a bail 55 which is pivotally mounted upon a pin 35 56 and has an extended finger 57 which is normally engaged with the fixed end of a latch member 58.

Said latch member is rotatably mounted upon the shaft 44 and is normally urged toward a 40 latched position by means of a spring 59 which is stretched between a tail portion 61 thereof and a fixed lug 62. A pin 62 extending vertically upward from the latch member 58 is normally engaged by a shoulder 79 of the latch tripping arm 47 as shown in Fig. 7 through the assistance of a spring 63 which is stretched between the lever 46 and the latch tripping arm 47.

With regard to the secondary clutch member, it will now be seen that upon engagement of a 45 letter with the trip finger 16, the sleeve 45 and lever 46 will be rocked from the position illustrated in Fig. 7 to the position of Fig. 9 and thereby cause the latch tripping arm 47 to withdraw the latch member 58 from its engagement with the finger portion 57 of the bail 55 and permit the pawls 52-52 to become engaged in driving relation with the rotating ratchet wheel 48. Upon said pawl engagement the plates 54-54 will be rotated through one revolution, the limit 50 of movement being controlled by means of the latch member 58 upon returning to its normal position. A back stop 86 is also provided which is adapted to engage a notch 87 in the lower plate 54 to prevent any rebound. A plate 64, 65 which is positioned directly above the upper plate 54 and which is connected therewith by means of a pin 56, as shown in Fig. 8, will also be rotated.

Associated with this last mentioned plate 64 is 70 the means which is provided for delaying the trip action of the main clutch 21. Said means includes a disk 65, having a central hub portion 66 projecting upwardly therefrom which is mounted in a rotatable and vertically slidable relation within 75

a bushing 67, rotatably supported in a bracket 68. A hand knob 69 is provided at the upper end of said hub portion by means of which the disk 65 is adapted to be raised out of contact relation with 5 its adjacent plate 64. A spring 71 is provided around the hub portion 66 to effect a tension between the lower flanged end of the bushing 67 and the upper surface of a disk 65, to thereby force the disk 65 against the plate 64. Another spring 10 83 is tensioned against the upper surface of the plate 64 within a recess in the hub 51 to prevent the plate 64 from being withdrawn with the disk 65 when said disk 65 is raised by the knob 69.

A plurality of openings 72 are arranged in the 15 plate 64 in a manner indicated in Fig. 9. Associated with said openings 72 is a detent pin 73 which is fixed within the disk 65 and is adapted to be engaged with any one of said openings 72 when the upper plate 65 is raised by the knob 69 20 and rotated. A roller 74 is also carried by the disk 65 on its upper surface, the same being mounted upon a pin 75 which is secured within the disk 65.

By means of this arrangement, it will be seen 25 that the roller 74 may be placed in any one of a plurality of positions. An adjustment of the position of the roller is made by pulling upward upon the knob 69 to withdraw the detent pin 73 from engagement with an opening 72, then rotating 30 said knob to bring the detent pin 73 into engagement with another of the openings 72. An indicator arrow 88 may be provided on the knob 69, to cooperate with a graduated portion indicated by the positions 1, 2, 3 and 4 on the upper 35 face of the bracket 68, Fig. 1, to assist in adjusting the position of the detent 73.

Associated with said roller 74 is a cam member 76 which is formed as part of an arm 77, which arm is pinned to the shaft 44 as best shown in 40 Figs. 3 and 5. The cam 76 is normally maintained in the path of the roller 74, as in Fig. 6. When a tripping operation of the trip finger 16 is effected by the engagement of a letter therewith, the secondary clutch member will be tripped 45 to cause the disk 65 to be rotated. The roller 74, upon reaching the cam member 76, will cause the arm 77 to be rocked from the position shown in Fig. 6 to the position in Fig. 10. The arm 77 and the aforementioned trip arm 42, Fig. 3, are both pinned to the shaft 44, therefore, the rocking of 50 said arm 77 will cause the trip arm 42 to be rocked from the full line position of Fig. 3 to the dotted line position, which, through the rocking of the abutment member 29, will cause the rocker member 24 to be rocked about its axis to release the main clutch 21.

When the disk 65 is adjusted so as to maintain the roller 74 in engagement with the cam member 76 as shown in Fig. 6, during the normal rest 55 period, the tripping of the secondary clutch will immediately effect the tripping of the main clutch 21 after the engagement of a letter with the trip finger 16, which action will result in the printing of a stamp impression and postmark impression upon the letter in the position shown in Fig. 11. The stamp impression is made from the die indicated at S, Fig. 4, and the postmark impression is made from the die P which is removably mounted in the die support. When the position 60 of the roller 74 is adjusted to any of the other positions, as provided for in the particular structure illustrated, the stamped impression may be printed at any one of the positions indicated at A, B, C, or D as shown in Fig. 12. If only a 65 single stamp impression is taken in either of these

positions the postmark stamp will also be printed.

It is also possible to print a plurality of stamped impressions with a single postmark stamp impression in the particular order shown in Fig. 12 by removing the postmark die P from the die 5 support and permitting the operation of the machine for the printing of the stamp in the positions A, B, and C during three different runs of the letter thru the machine, then reinserting the postmark die P before printing the fourth stamp 10 impression D, which impression will then be accompanied by the postmark impression.

After the tripping and printing operations are effected, the latch member 58, which is maintained in a released position by the periphery of 15 the upper plate 54, as in Fig. 10, will be restored to its original latching position by the action of the spring 59 when a cut away portion of the plate 54, indicated at 78, Fig. 10, passes the engaging end of the latch member. A stop 79 20 limits the return movement and fixes the position of the latch member in the path of the bail finger 57 to permit the latch member to be engaged by said finger 57 after the secondary clutch has completed one full revolution.

The latch tripping arm 47, being controlled by 25 the position of the trip finger 16, will thus remain in its tripped position until the end of the letter passes said trip finger. This time will vary in accordance with the different lengths of envelopes used, to the extent that the latch tripping arm 47 may be moved to its normal set position either before or after a printing operation is completed. If it is moved after a printing operation is completed, the latch member 58 will have 30 been restored to its set position before the movement of the tripping arm 47, but upon reaching the reset position, the said tripping arm will snap over the pin 62 to bring the latch or shoulder portion 79 thereof into operative relation with 35 said pin 62. The position of the shoulder 79 will be determined by the position of the trip finger 16 and the position of the trip finger is determined by the position of trip arm 42, Fig. 3, in conjunction with the shoulder 41 of the pull 40 rod 39.

Instead of providing a detent pin 73 in the plate 45 65 and openings 72 in the plate 64, each of said plates 64 and 65 may be provided with ratchet teeth to provide a ratchet clutch as indicated in 50 Fig. 14, each of the plates 64 and 65 being indicated here as 64a and 65a respectively. This will permit of a fine adjustment which will be particularly useful for conditions where a stamp impression is to be placed within a certain area 55 or within a certain fixed distance with respect to the edge of the letter or other articles such as a card. For example, it may be desired to utilize the machine for the printing of tax stamps upon cards which have predetermined positions 60 for said stamps as provided for by the ruled boxes or spaces as indicated on the card in Fig. 13.

If desired the roller may also be adjusted individually by arranging same in a manner indicated in Fig. 15, wherein the roller indicated as 65 74a is mounted on a sleeve 84 and said sleeve is adapted to be adjusted within a slot 85 in a disk 65b. By means of a bolt 86 which is passed through the sleeve and seated in the disk 65b, the said sleeve is adapted to be clamped in an adjusted 70 position when a nut 87 is tightened on said bolt.

It will thus be seen that a device of this character can be made very flexible and lends itself to the printing on various articles, wherein a tripping device is to be actuated by the leading 75

edge of an article which is being moved to a printing position.

Having described the invention, I claim:

1. In a device of the character described, a printing member adapted to print impressions upon moving articles, a trip member actuated by said articles, a second trip member controlled by said first trip member and arranged to release said printing member to effect a printing operation on an article, and means to adjustably time the operation of said second trip member, whereby impressions may be made within predetermined positions in accord with the said adjustment.
2. In a device of the character described, a printing member, means to move articles to a printing position, a tripping member operable upon engagement of an article therewith, printing member actuating means, and a second tripping member cooperating with said first tripping member to delay the operation of said printing member by the actuating means.
3. In a mailing machine, a printing member arranged to print stamp impressions upon letters, means to move the letters to a printing position, a drive to effect a printing operation, a tripping device arranged in the path of the moving letters and operable upon engagement of a letter therewith, and means controlled by said tripping device to delay the effective printing operation of said printing member after tripping is effected.
4. In a device of the character described, a printing member arranged to print an impression on articles which are moved to a printing position, a tripping member operable upon engagement of an article therewith, and adjustable printing member releasing means controlled by the tripping member arranged to effect the printing of an impression in any one of a number of predetermined positions on the article.
5. In a mailing machine, a printing member arranged to print a stamp impression upon letters when the letters are moved to a printing position, means to effect a printing operation including one tripping device operable upon engagement of a letter therewith and a second tripping device controlled by the first tripping device, and means to control the time for actuating the second printing device, whereby the stamp impression may be placed in one of a plurality of predetermined positions within a predetermined area on said letters.
6. In a mailing machine, a printing member arranged to print a stamp impression upon letters when the letters are moved to a printing position, means to effect a printing operation including one tripping device operable upon engagement of a letter therewith and a second tripping device controlled by the first tripping device, and means including a clutch associated with the second tripping device and having an adjustable striker member associated therewith to provide for the tripping of the printing member, whereby the stamp impression may be placed in any desired position within a predetermined area on said letters.
7. In a mailing machine, a printing member arranged to print a stamp impression upon letters when the letters are moved to a printing position, means to effect a printing operation including a tripping device operable upon engagement of a letter therewith, an adjustable trip member actuated by said first named tripping device, and means associated with said adjustable trip member to start the operation of the printing member at a predetermined period after engagement of the letter with the first named tripping device.
8. In a mailing machine, a printing member arranged to print a stamp impression upon letters when the letters are moved to a printing position, means including a clutch device associated with the printing member to effect a printing operation, a tripping device operable upon engagement of a letter therewith, and means including a second clutch device controlled by said tripping device and interposed between said first named clutch and tripping device to delay the operation of the first named clutch after tripping by means of the letter is effected.
9. In a device of the character described, a printing member, means including a clutch to control said printing member to effect a printing operation on an article, a tripping member, a second clutch interposed between said tripping member and first named clutch, and means to adjust the operation of said second clutch, whereby impressions may be made within predetermined positions in accord with the said adjustment.
10. In a device of the character described, a printing member, means including a clutch drive to control said printing member to effect a printing operation on an article, a tripping member operable upon engagement of an article therewith, a secondary clutch tripping means operable by said tripping member, and an adjustable trip member associated with means to variably adjust said secondary clutch tripping means, whereby impressions may be made within predetermined positions in accord with the said adjustment.
11. In a printing device having a printing member normally maintained in a rest position, means for moving articles into printing relation with the printing member, an actuating member arranged in an uncoupled relation with the printing member and operable to rotate said printing member upon the approach of an article to the printing position, a tripping member operable when engaged by an article, and means for timing the coupling of the actuating member with respect to the action of the tripping member whereby printing is effected at one of a plurality of predetermined positions on each article.
12. In a printing device having a printing member normally maintained in a rest position, means for moving articles into printing relation with the printing member, an actuating member including a clutch adapted to be coupled with the printing member and operable to rotate said printing member upon the approach of an article to the printing position, a tripping member operable when engaged by a letter, and means including a manually adjustable clutch tripping member for timing the coupling of the actuating member with respect to the action of the tripping member whereby printing is effected at one of a plurality of predetermined positions on each article.
13. In a printing device having a printing member and a drive to actuate same, means for moving articles into printing relation with the printing member, a clutch associated with the drive and adapted to be tripped to effect a printing operation when the article has reached a predetermined position with relation to the printing member, a trip member positioned in the path of said moving articles, and means associated with the trip member and clutch to delay the tripping of the clutch for a predetermined period after the trip member is engaged by an article.
14. In a printing device having a rotary printing member and a drive to rotate same, means for

moving articles into printing relation with the printing member, a clutch associated with the drive and adapted to be tripped to effect a printing operation when the article has reached a predetermined position with relation to the printing member, a trip member positioned in the path of said moving articles, and manually adjustable means interposed between the trip member and clutch to delay the tripping of the clutch for a predetermined period after the trip member is engaged by an article.

15. In a device of the character described having a printing member normally maintained in a rest position, means for moving articles into printing relation with the printing member, a drive, a clutch interposed between said drive and printing member, a trip associated with said clutch, a second clutch, a continuously driven member associated with the second clutch, a latch normally maintaining the second clutch in a rest position, a latch actuating member associated with the moving articles and arranged to release the second clutch member upon contact by an article, and an adjustable trip actuating member movable with the continuously driven member to engage the said trip after the release of the latch to thereby next release the first named clutch member.

16. In a device of the character described, a printing member arranged to print an impression on articles which are moved to a printing position, a tripping member operable upon engagement of an article therewith, a main clutch member associated with the printing member and normally maintained in a non-driving relation, a secondary clutch associated with the tripping member, a latch to normally maintain said secondary clutch in a non-driving position, a latch tripping member movable with the first named tripping member to release said latch and thereby trip said secondary clutch, a main clutch tripping means, and means movable with the secondary clutch to actuate the main clutch tripping means.

17. In a device of the character described, a printing member arranged to print an impression on articles which are moved to a printing position, a tripping member operable upon engagement of an article therewith, a main clutch member associated with the printing member and normally maintained in a non-driving relation, a secondary clutch associated with the tripping member, a latch to normally maintain said secondary clutch in a non-driving position, a latch tripping member movable with the first named tripping member to release said latch and thereby trip said secondary clutch, a main clutch tripping means, and a manually adjustable member movable with the secondary clutch to actuate the main clutch tripping means.

18. In a device of the character described, a printing member arranged to print an impression on articles which are moved to a printing position,

a tripping member operable upon engagement of an article therewith, a main clutch member associated with the printing member and normally maintained in a non-driving relation, a secondary clutch including a continuously rotatable ratchet gear associated with the tripping member, pawls arranged to coact with said ratchet gear, a latch to normally maintain said pawls free from engagement with the ratchet gear, a latch tripping member movable with the first named tripping member to release said latch and thereby permit the engagement of the pawls with the ratchet to effect the drive of the secondary clutch, a main clutch tripping means, and means movable with the secondary clutch to actuate the main clutch tripping means.

19. In a device of the character described, a printing member arranged to print an impression on articles which are moved to a printing position, a tripping member operable upon engagement of an article therewith, a main clutch member associated with the printing member and normally maintained in a non-driving relation, a secondary clutch associated with the tripping member, a latch to maintain one portion of said secondary clutch in a rest position, a latch tripping member movable with the first named tripping member to trip said secondary clutch and cause the drive of the normally non-driven portion, a striker member movable with said normally non-driven portion when the secondary clutch is driven, a main clutch tripping means, and means whereby the striker member is adapted to actuate the main clutch tripping means a predetermined period after the latch is tripped.

20. In a device for marking moving articles, a printing member, a drive, a clutch associated with said printing member, a stop to normally retain said clutch in a rest position and drive and adapted to be tripped to effect a printing operation when the article has reached a predetermined position with relation to the printing member, a trip member adapted to be actuated by contact of the articles therewith, and connections between said trip member and clutch stop including means whereby the tripping of the clutch is delayed until the article has advanced to a printing position.

21. In a printing device having a rotary printing member and a drive to rotate same, means for moving articles into printing relation with the printing member, a clutch associated with the drive and adapted to be tripped to effect a printing operation when the article has reached a predetermined position with relation to the printing member, a trip member positioned in the path of said moving articles, and means including an adjustable trip member interposed between the first named trip member and clutch to delay the tripping of the clutch for a predetermined period after the trip actuating member is engaged by an article.

JACOB W. OGDEN.

CERTIFICATE OF CORRECTION.

Patent No. 2,130,897.

September 20, 1938.

JACOB W. OGDEN.

It is hereby certified that error appears in the printed specification of the above numbered patent requiring correction as follows: Page 5, second column, lines 39 to 42, claim 20, strike out the words "and drive and adapted to be tripped to effect a printing operation when the article has reached a predetermined position with relation to the printing member" and insert the same after "member" and before the comma in line 38, same claim; and that the said Letters Patent should be read with this correction therein that the same may conform to the record of the case in the Patent Office.

Signed and sealed this 15th day of October, A. D. 1940.

(Seal)

Henry Van Arsdale,
Acting Commissioner of Patents.
